UNITED STATES PATENT OFFICE.

WILLIAM W. SWEETLAND, OF EDWARDSBURG, MICHIGAN.

DESIGN FOR A FLOOR-REGISTER.

SPECIFICATION forming part of Design No. 18,909, dated February 5, 1889.

Application filed October 5, 1888. Serial No. 287,338. Term of patent 14 years.

To all whom it may concern:

Be it known that I, WILLIAM W. SWEETLAND, a citizen of the United States, residing at Edwardsburg, in the county of Cass and State of Michigan, have invented a new and original Design for a Floor-Register, of which the following is a specification.

My invention relates to a design for floor-registers, and it is more fully described hereinafter in connection with the accompanying drawing, wherein the figure represents a plan view thereof.

The floor-register is in the shape of an isosceles triangle, one of the angles of which is a right angle to fit in the corner or angle of a room. The base of the triangle is a straight line. The register-face A fits in an outer border or band, B, and within the said register-

face is arranged the grating D, consisting of the parallel lines *d* and the cross-lines *d'*, intersecting the parallel lines.

The leading feature of this design, as will be seen, is the peculiar shape of the register-face.

Having thus described the invention, I claim—

The design for a floor-register, consisting of a triangular register-face inclosing a grating, substantially as specified and shown.

In testimony that I claim the foregoing as my own I have hereto affixed my signature in presence of two witnesses.

WILLIAM W. SWEETLAND.
